UNITED STATES PATENT OFFICE.

MILDRED C. SCHMOLZE, OF NEW YORK, N. Y., ASSIGNOR TO FRANKLIN SIMON & COMPANY, OF NEW YORK, N. Y., A CORPORATION OF NEW YORK.

DESIGN FOR A BATHING SUIT.

Application filed December 17, 1924. Serial No. 11,730. Term of patent 3½ years.

To all whom it may concern:

Be it known that I, MILDRED C. SCHMOLZE, a citizen of the United States, and a resident of the city of New York, borough of Manhattan, in the county and State of New York, have invented a new, original, and ornamental Design for Bathing Suit, of which the following is a specification, reference being had to the accompanying drawing, forming part thereof, wherein the suit is distinguished by having the upper and lower part of the top piece formed of material having dissimilar colors with an

ornamental tortuous connecting line arranged therebetween.

Figure 1 is a perspective view of a bathing suit, showing my new design.

Figure 2 is a fragmentary enlarged view showing the ornamental connecting line between the upper and lower part of the top piece.

I claim:

The ornamental design for a bathing suit, substantially as shown and described.

MILDRED C. SCHMOLZE.
